MANUFACTURE OF WORSTED ROVING

Rene J. de Lathauwer, Hawthorne, N. J.

Application March 15, 1944, Serial No. 526,580

2 Claims. (Cl. 19—130)

1

In the treatment of wool fibers to produce a sliver in condition for spinning into worsted yarn the fibers are made subject to drawings in a succession of drawing machines, usually seven or more. In the first several machines, as the first three or four, a gill-bed, and in the remaining machines, a porcupine roll, is employed between the feed or retaining rolls and the delivery or drawing rolls, each such expedient being active, while made to advance at a speed between those of the corresponding feed and delivery rolls, to effect what I herein term a slip-draft combing, or to hold back those fibers that are not actually nipped by the delivery rolls and that would otherwise, as an incident merely of friction existing between them and the fibers actually so nipped, be advanced by and with the latter fibers, thus to defeat the purpose of the drawing operation or the effecting of as uniform lengthwise dispersion of all the fibers as possible. Incidentally, as is well known to workers in this art, the sliver can withstand and requires a more strenuous slip-draft combing in the early part of the whole treatment than in the later part thereof where it approaches or actually attains a quite frail condition, wherefore well known expedients are used, that is, gill-beds, with their closely related and numerous pins or gills, are used in the early part of the whole treatment and porcupine rolls, with more widely spaced and less numerous pins or quills, are used in the later part; and these two expedients differ in other respects affecting the disposition of their pins. In respect to any one of the several drawings the conditions are as follows: At least two separately formed slivers, each a more or less initially cross-sectionally round or other than flat strand, doubled (that is, lying side by side and in close contact with each other), pass between the feed rolls and the delivery rolls, being meanwhile subjected to the slip-draft combing action of the gill-bed or the porcupine roll, as the case may be, whereby they come to exist blended and merged into what is a unit or single sliver considerably greater in length than either, and of less weight per unit of length than the combined weight, of its component slivers, having become more or less flattened in the process. Following each gill-drawing operation such sliver is next subjected to a false-twisting operation effected by a back-and-forth rotated funnel, and following each porcupine-roll drawing operation the sliver is next subjected to a rolling operation effected by a pair of endless aprons which are advanced with the sliver and also reciprocated transversely thereof and oppositely

2 to each other, thus developing the sliver to more or less cross-sectionally round and condensed state. Following the condensing the sliver, or what as it now exists is known as a roving in this particular art, is formed into a wound mass, as on a suitably rotated roll or core, and thus "balled" in preparation to undergo again these steps in the next succeeding drawing operation or, the last drawing being completed, to pass to the spinning operation.

The object of the present invention is to produce a sliver product, or roving, in condition for spinning into worsted yarn which shall be substantially as completely and evenly or uniformly drafted as by the conventional procedure but to do so in a way to reduce the equipment necessary and obtain a considerable saving in power, time and labor.

To this end, instead of passing the material through the seven or more stages indicated in order finally to produce a roving suitable for spinning into worsted yarn, I proceed as follows: Each of at least two slivers is subjected, while being continuously advanced, first to simultaneous drawing and slip-draft combing and thereafter to drawing and slip-draft combing of which the former combing is more strenuous than the latter and meanwhile the intake speed of the second drawing is preserved substantially equal to the output speed of the first drawing, whereupon the thus-treated sliver is condensed and packaged; thereupon the thus-treated slivers are combined to form a doubled sliver and such doubled sliver is subjected to the same treatment as each sliver has undergone inclusive of at least the condensing thereof, thus to produce a roving in condition, at least as to draft and condensation, to pass to the spinning operation, though usually following such condensing and during the advance of the doubled sliver it will also be packaged. Whether or not the first-named slivers are simultaneously treated is of course immaterial. Further, each of such first-named slivers will in practice usually, itself, comprise two or more sliver-components, as I herein term them. Preferably in each stage (to wit, in which each of the first-named slivers is treated, and in which the doubled sliver is treated) blending of the fibers by transversely compacting them is effected. By following this procedure the number of drawings is reduced to four each, instead of seven or more, and the condensings and packagings or ballings are reduced to two each, instead of seven or more, with a consequent considerable economy in equipment, labor, time and power.

In the annexed drawing, both views appearing being diagrammatic,

Fig. 1 is a side elevation of the improved system; and

Fig. 2 a plan of the lower elements shown in Fig. 1, with the slivers appearing in broken outline.

At 1—1a are the feed rolls and at 2—2a—2b are the delivery rolls for the first drawing operation of the first stage. So as to exert pressure on the slivers roll 1 rests as usual on roll 1a and roll 2 on the pair of rolls 2a—2b. Between the feed rolls and the delivery rolls is any usual type of gill-bed 3 used in wool drawing. Each of the rolls 1a and 2a—2b is the positively driven roll of its group, roll 1 being driven from roll 1a and roll 2 from roll 2a—2b by traction.

Aft of the delivery rolls are fixed chutes or funnels x each of which narrows and so compacts the fiber mass presented to it transversely, they discharging close to the nips of the feed rolls next to be referred to.

At 4—4a are the feed rolls and at 5—5a—5b are the delivery rolls for the second drawing operation of the first stage. So as to exert pressure on the slivers roll 4 rests on roll 4a and roll 5 on the pair of rolls 5a—5b. Between these feed rolls and delivery rolls is the pair of rolls 6—6a, roll 6 resting on roll 6a so as to exert pressure on the slivers but being as usual in offset relation thereto in the direction of advance of the sliver. Between rolls 6—6a and the delivery rolls is the porcupine roll 7. Rolls 4a, 5a and 5b, roll 6a and the porcupine roll 7 are positively driven, rolls 4, 5 and 6 being driven by traction from the rolls on which they respectively rest.

Aft of delivery rolls 5—5a—5b are fixed chutes or funnels y which narrow the sliver transversely, discharging close to condensing means thus:

The condensing means consists of a lower pair of rolls 8, embraced by an endless apron 9, and three upper rolls 10, embraced by an endless apron 11, the lower apron having its upper stretch horizontal and the upper rolls being of such relative diameters and so arranged that the upper apron coacts with the lower apron to roll and thus condense the slivers passed between them when the aprons are subjected to reciprocation transversely of the slivers and reversely to each other in the well known manner.

To the right or aft of the condensing means is the balling means comprising a lower roll 12 and a roll 13 resting thereon and on which the winding or balling is effected. Roll 12 is positively driven.

Rolls 1a, 2a, 2b, 4a, 6a, 7, 5a, 8 and 12 are all driven in the same direction, or here so that the slivers are advanced to the right.

Roll 2a is driven at a faster speed than roll 1a so as to effect the first drawing, and rolls 5a—5b are driven at a faster speed than roll 4a so as to effect the second drawing. And of course rolls 8 and 12 are driven at at least a speed not less than that imparted to the slivers as delivered by the second drawing means, thus to perform their intended functions of condensing and balling.

But feed roll 4a of the second drawing means is driven at the same peripheral speed as the delivery rolls 2a—2b of the first drawing means.

In Fig. 2 four pairs of sliver-components, as a—a in each pair, are shown by way of example. Those of each pair exist side by side and in contact with each other, as usual, on entering the first drawing means and in that sense doubled;

in any event each of the four masses of fibers here shown exists as what I shall hereinafter, in this description and in the appended claims, term a "sliver." Such sliver, attenuated by the gills and thereupon reduced in width by funnel x, and with its fibers more or less blended, is delivered by the delivery rolls 2—2a—2b to the feed rolls 4—4a of the second drawing means, to wit, in neutral state in transit from rolls 2—2a—2b to rolls 4—4a insofar as draft or lack of draft is concerned because the rolls 2—2a—2b and 4—4a rotate at the same peripheral speed. The sliver, here by the porcupine roll attenuated, and again reduced in width by funnel y, and with its fibers still more blended, is then subjected to the rolling and hence condensing action of the aprons and finally is balled at 12—13, for this latter purpose being delivered, as usual, via a spout 14 to the balling means with a neighboring roving that has been produced in the same way as itself.

This completes the first stage as it will preferably be practiced in performance of my invention. To complete the treatment to produce a roving in the state required for spinning the product, or thus treated sliver, of the first stage is made to undergo again the same operations as in said first stage, that is to say, when combined with a sliver that has been treated in the same way and so as to form therewith what I term in the appended claims a "doubled sliver."

Of course, according to my treatment, as well as in the case of the conventional treatment hereinbefore set forth, the more strenuous primary slip-draft combing action, as by the gills, is necessary and possible because of the greater stability and cruder character of the slivers, and the less strenuous secondary slip-draft combing action, as by the porcupine roll, is necessary and possible because of the then reduced stability and more refined character of the slivers. But my invention involves providing for two successive drawing operations respectively accompanied by slip-draft combings of which the one appertaining to the first drawing is more strenuous than that appertaining to the second drawing and in further rotating the feed rolls for the second such operation at the same peripheral speed as that of the delivery rolls of the first, or, in other words, entering the slivers to the second drawing at an input speed which is equal to the output speed of the first drawing. If that is done, thus affording one stage in the whole treatment, and such is then repeated, thus to afford the second stage, there need be only four drawings, with their four slip-draft combings, two condensings and two ballings, and, as practice has shown, the resulting product is as good in quality as that produced by the conventional procedure.

The condensing and packaging are herein shown and described as effected after the manner of what is known as the "French" method of treating wool fibers in preparation for spinning; but it is to be understood that my invention is not correspondingly limited, inasmuch as those steps could obviously be performed in accordance with what is known as the "Bradford" method of treating wool fibers in preparation for spinning, to wit, by resort to fliers and bobbins by which the slivers would be more or less twisted and in that state wound on bobbins or spools.

Having thus fully described my invention, what I claim is:

1. The method of drawing wool fibers to produce a roving in condition for spinning into

75

worsted yarn which consists in subjecting each of at least two slivers comprising such fibers, and while continuously advancing such sliver, first to simultaneous drawing and slip-draft combing such as by gilling and thereafter to simultaneous drawing and slip-draft combing such as by the use of porcupine rolls of which the former combing is more strenuous than the latter and meanwhile maintaining the intake speed of the second drawing substantially equal to the output speed of the first drawing, thereupon condensing and packaging the thus-treated sliver, and thereafter combining said thus-treated slivers to form a doubled sliver and subjecting such doubled sliver, while continuously advancing the same, first to simultaneous drawing and slip-draft combing and thereafter to simultaneous drawing and slip-draft combing of which the

former combing is more strenuous than the latter and meanwhile maintaining the input speed of the second drawing substantially equal to the output speed of the first drawing of such doubled sliver, and finally condensing the thus-treated doubled sliver.

2. The method set forth in claim 1 characterized by compacting transversely the fibers of the first-named sliver between the two first-named drawings and slip-draft combings and also between the latter drawing and slip-draft combing and condensing of such sliver, and compacting transversely the fibers of said doubled sliver between the two drawings and slip-draft combings thereof and also between the latter drawing and slip-draft combing and condensing of such doubled sliver.
